Copy 10, 452, 11

Charles Foddy
Boston Patent dated April 26th 1815 and Re-
corded anno May, 26th, 1815.

The Schedule referred to in these Boston Patent and
making part of the same containing a description in the
words of the said Charles Foddy himself of his
improvements in Stoves.

This Stove may be made either of steel or cast iron or
any other suitable materials, it consists of thirteen plates,
at one end of the stove is a furnace of the width of the
stove, the depth and height according to the size of the
stove, say from 9 to 12 inches depth, height 4 $\frac{1}{2}$ width and
in length the width of the stove.

The fire is made on the bottom of the plate of the stove
and the remainder of the stove consists of an oven of the
height of from 6 to 9 inches, above the oven is a flue
leading from the furnace of 2 $\frac{1}{2}$ inches in height, and
the width of the stove, this leads to the end of the stove
furthest from the furnace and then being contracted to 2
inches ascends to the top and is carried under the top plate
to within 4 $\frac{1}{2}$ inches of the other end, then descends to the
plate over the furnace, and again ascends to the opening
which carries of the smoke, the rest of the stove forms
a second oven which will be from 18 to 24 inches in
length according to the size. By this construction the
fire being made at one end and adjoining the plates of
the bottom oven, is carried over the same and also all
warmed the upper oven giving a more uniform heat than
other stoves. (Down in the furnace) and also in the flue
leading directly from the opening of 5 $\frac{1}{4}$ inches in length
and 1 $\frac{1}{4}$ inch in depth for receiving projecting bars from

holes which are made in said openings and removed as here
seen, these holes are from 9 to 11 inches long according to the
size of the boilers, and in width and thickness to fit the
openings that are in the stove. In the top plates of the
oven are small openings for carrying of the steam which
may arise from cooking etc. The boilers may be made
of copper tin sheet or cast iron, or any other suitable ma-
terials and of any size required the boilers for boiling chicks
may be made of wood with copper tubes, or other suitable
materials.

The stove may also be constructed thus, with 12 plates, the
furnace at one end of the stove, from 9 to 12 inches in width
and in length the width and the height of the stove, the fire
ascends to the top of the stove, and there is carried off in a
flue of 3 inches in depth and the width of the stove to with-
in 2½ inches of the other end of the stove, then the flue is
contracted to 2 inches and descends to within 4½ inches
of the bottom and then takes a direction along the bottom of the
oven until it comes at the back plate of the furnace and then
returns to the further end in a flue of 2 inches and then
ascends to the opening which carries off the smoke in a flue of 2
inches also, all the flues are of the whole width of the stove, this
leaves the middle of the stove open and is converted into an
oven by means of a door fast on hinges and will be of any
size according to the size of the stove, say in general from 15
to 24 inches in length & from 8 to 12 inches in depth and
is surrounded with heat.

The top plate of the stove has from 2 to 3 apertures me-
diately over the fire, the others between that and the further end
of the stove, in they may be placed boilers of any size the stove
will admit of, there are also openings in the furnace for re-
moving projecting tubes of boilers the fire being at one end of the
stove the furnace may have folding doors and being left open

204

show the fire the same as a Franklin stove and at the same time heat the stove etc.

knowing many advantages which these stoves possess over others we may enumerate the following they consist of one to two doors and has attached to them from three to five boilers according to the size of the stove all of which may be put in operation with the same fire which heats the stove of which there may be no operation. Roasting, Baking, Boiling all at the same time, and does not consume more than one half the wood that common baking oves, a boiler containing from 6 to 12 quarts will boil in 15 minutes and according to the size the longer time will be required for them to boil — and the greater advantage is that their price is within the reach of the poor in general, so as they can save the one half the fuel and keep their families more comfortable. Some of these gentlemen that have them now or now say they do not consume more than one quarter of a cord of wood in a winter month with one advantage of doing all their cooking & washing with the small fire.
